UNITED STATES PATENT OFFICE

JOHN VAN BUREN, OF BROOKLYN, NEW YORK

WRAPPING MACHINE

Application filed November 18, 1931. Serial No. 575,751.

This invention relates to wrapping machines and the machine about to be described as an embodiment of the invention has been designed particularly for wrapping cakes of soap, although, of course, the invention is not limited to this specific use.

This invention has been worked out in connection with the type of wrapping machine shown in Van Buren Patent 1,746,448 granted February 11, 1930. In the machine disclosed therein, the wrapper is folded around the article and the ends are then folded across the ends of the article in opposite directions. Some difficulty has been encountered in maintaining the wrapper tight around the article since it tends to loosen the folds extending in one direction as the article is discharged from the folding mechanism into the guideway or delivery chute.

This invention has for its salient object to provide means for pulling the wrapper tight around the article and in maintaining the wrapper tight as the wrapped article is fed into the guideway or delivery chute.

Further objects of the invention will appear from the following specification taken in connection with the drawings, which form a part of this application, and in which

Fig. 1 is a side elevational view, partly in section, showing a machine constructed in accordance with the invention;

Fig. 2 is a vertical sectional elevation 35 through the folding mechanism;

Fig. 3 is a horizontal sectional elevation at the bottom of the folding mechanism;

Fig. 4 is a sectional elevation at right angles to Fig. 2, showing the lower end of 40 the folding mechanism and the plunger for discharging the wrapped articles into the guideway or delivery chute.

Fig. 5 is a sectional elevation taken at right angles to Fig. 4.

45 The invention briefly described consists of a machine comprising folding means for folding the wrapper around the article and means for folding the ends of the wrapper in opposite directions across the ends of the article. The end folding means comprises

supplemental means for tightening the wrapper around the article prior to the operation of last folding means. The last folds are formed by pushing the wrapped article into the guideway or delivery chute 55 and the end folds formed by the folding means prior to the last folds extend in a direction opposite to the direction of the feeding movement of the articles. For this reason means in the form of positively driven 60 rollers are provided for tightening the wrapper and holding the end folds as the article is fed into the chute.

Further details of the invention will appear from the following description. 65

In the particular embodiment of the invention illustrated in the drawings, there is shown a portion of the machine disclosed in the drawings of Patent 1,746,448 above referred to. The entire machine is not il- 70 lustrated as this is not deemed necessary.

The wrappers are fed downwardly in the guideway 10 and pass between suitably driven feed rollers 11 and 12 into the path of movement of the articles to be wrapped 75 such as cakes of soap 13.

The articles move down an inclined support 14 and successively drop on a shelf 15. A reciprocating plunger 16 feeds the cakes from the shelf 15 into the open end of 80 a pocket or tumbler block 20.

As the cakes are fed into a pocket or tumbler block by the plunger 16 the wrapper is folded around the three sides of the cake and fingers 22 and 23 carried by the 85 tumbler block or pocket tuck the ends of the wrappers as shown at 24 and 25.

The free edge of the wrapper is folded against the other edge as the cake and the wrapper are discharged from the tumbler block into the vertically disposed folding mechanism 30.

The other end of the pocket or tumbler block 20 is formed by a plate which is carried by rods 32. 90

These rods are engaged at their upper ends by a pushed plate 33 carried by a lever 34 which is mounted on a fixed pivot 35 and is actuated by a crank pin 36 carried by a crank 37 and disposed in a slot 38 100

formed in the lever. As the lever is actuated in a clockwise direction, viewing Fig. 1, the rods 32 and the plate 31 will be pushed downwardly and will discharge the cake and wrapper into the folding mechanism 30.

The tumbler block or pocket is mounted on a pivot 40 and is periodically oscillated from receiving to discharging position. 10 This oscillation may be accomplished in a suitable manner and in Fig. 1, the shaft 40 of the pocket 20 has mounted thereon a gear 41 which engages the rack 42 carried by a pitman 43 having a roller 44 engaged by a 15 cam 46 carried by the shaft 47 on which the crank pin 36 is mounted. The cam is so designed as to reciprocate the pitman 43 and oscillate the tumbler block or pocket at the required periods in the cycle of operation of the machine.

The cakes or articles are discharged from the tumbler block or pocket 20 downwardly into the folding mechanism 30 which is provided with upwardly extending fingers 50 25 and 51 which engage the wrapper and tuck the ends thereof as shown in 52 and 53.

The folding mechanism is also provided along each edge thereof with curved slots 54 which engage the end folds at one face of 30 the cakes and fold them across the ends of the cake.

In the machine disclosed in the patent above referred to the cakes are discharged from the bottom of the folding mechanism 35 30 and are forced into the guideway, the sides of the guideway engaging the ends at the other face of the cake and folding them against the end folds already formed.

In the machine disclosed in this application further means has been provided for 40 tightening the wrapper around the cake before the wrapped cake is fed into the guideway. It was found that the end folds formed by the arcuate slots 54 tended to unwrap as the cake and wrapper are fed into the guideway since the folds "A" extend in the direction opposite to the direction of the feeding movement of the cakes.

In order to tighten the wrapper around 50 the cake, rollers 55 and 56 are rotatably mounted at the sides of the folding mechanism 30, below the slots 54.

The rollers 55 and 56 are mounted on spindles 57 and 58 to which are secured gears 55 59 and 60 which mesh with gears 61 and 62 carried by a shaft 63 which may be driven in a suitable manner as by a sprocket wheel 64. The rollers 55 and 56 are continuously rotated.

60 The direction of rotation of the rollers 55 and 56 is indicated by the arrows in Fig. 3 and it will be noted that these rollers frictionally engage the end folds "A" and by their engagement pull the wrapper tightly around the ends of the cake. The rollers

are driven at a faster rate of speed than the rate of feed of the cakes into the guideway and this point should be particularly noted since by means of this faster rotation the wrapper is tightened around the cake.

70 As the cakes are discharged from the folding mechanism they will be positioned on a shelf or table 70 between the rollers 55 and 56. When in this position they are engaged by plunger 71 which is connected by pitman 72 to a crank 73 carried by a shaft 74. As the shaft rotates the plunger 71 will be reciprocated and will push the wrapped cakes along the shelf or table 70 between walls 75 and 76. These walls engage the outer ends 80 "B" of the wrapper and fold them across the end folds "A". From the chute or guideway formed by the table 70 and the side walls 75 and 76 the cakes may be conducted to any suitable handling means such as conveyors.

Operation

The operation of the machine above described may be summarized as follows:

90 The articles or cakes 13 are fed down the incline 14 and into the tumbler block 20, when the block is disposed in horizontal position. The block or pocket is then oscillated to vertical position as shown in Figs. 1 and 2 and the plate 31 pushes the cake from the pocket into the folding mechanism. The tucks 24 and 25 are formed when the wrapper and cake are pushed into the pocket and the tucks 52 and 53 are formed when the cakes are pushed into the folding mechanism. The end folds "A" are formed by the curved slots 54 and as the cake is discharged from the bottom of the folding mechanism it is positioned between the rollers 55 and 56 which engage the end folds A, A and pull the wrapper tight around the cake. The wrapper is thus tightened around the cake and the end folds B, B are formed when the wrapped cake is pushed into the guideway along the table 70.

95 100 105 110 115 120 125 130 Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In a wrapping machine, means for folding a wrapper around an article, a guide way, means for feeding the wrapped article into the guide way and positively moving means for tightening the wrapper as the wrapped article is fed into the guide way.

2. In a wrapping machine, means for folding a wrapper around an article, a guide way, means for feeding the wrapped article into the guide way and means at the en-

trance to the guideway operating in the direction of feed of the article and at a faster rate of speed for tightening the wrapper as the wrapped article is fed into the guide way.

3. In a wrapping machine, means for folding a wrapper around an article, a guide way, means for feeding the wrapped article into the guide way and positively driven means disposed at the entrance to the guideway for tightening the wrapper as the wrapped article enters the guide way.

4. In a wrapping machine, means for folding a wrapper around an article, a guide way, means for feeding the wrapped article into the guideway and positively driven moving means operating in the direction of feed of the article and at a faster rate of speed for tightening the wrapper as the wrapped article is fed into the guide way.

5. In a wrapping machine, means for folding a wrapper around the sides and ends of an article, a guide way, means for feeding the wrapped article into the guide way, and means, located at the entrance to the guideway and operating on certain of the end folds for tightening the wrapper as the wrapped article is fed into the guide way.

6. In a wrapping machine, means for folding a wrapper around the sides and ends of an article, a guide way, means for feeding the wrapped article into the guide way and moving means operating on certain of the end folds and in the direction of feeding movement of the article for tightening the wrapper as the wrapped article enters the guide way.

7. In a wrapping machine, means for folding a wrapper around an article, a guide way, means for feeding the wrapped article into the guide way and rotating means for tightening the wrapper as the wrapped article is fed into the guide way.

8. In a wrapping machine, means for folding a wrapper around an article, a guide way, means for feeding the wrapped article into the guide way and rotating means engaging end folds at the ends of the article for tightening the wrapper as the wrapped article is fed into the guide way.

9. In a wrapping machine, wrapping mechanism, for folding a wrapper around an article, and for folding the wrapper in one direction across the end of the article, a guide way, means for pushing the article and wrapper from the folding mechanism into the guide way and, said end fold being made in a direction opposite to the direction of movement into the guide way and means for tightening said end fold and wrapper as the wrapped article enters the guide way.

10. In a wrapping machine, wrapping mechanism, for folding a wrapper around an article, and for folding the wrapper in one

direction across the end of the article, a guide way, means for pushing the article and wrapper from the folding mechanism into the guide way and, said end fold being made in a direction opposite to the direction of movement into the guide way and means operating in the direction of movement of the article into the guide way for tightening said end fold and wrapper as the wrapped article enters the guide way.
